FIG. 3.

FIG. 4.

Philip Dressler Inventor
By his Attorney
Geo W. Baumgardner

UNITED STATES PATENT OFFICE.

PHILIP DRESSLER, OF ZANESVILLE, OHIO, ASSIGNOR TO AMERICAN DRESSLER
TUNNEL KILNS, INC., OF NEW YORK, N. Y., A CORPORATION OF NEW YORK.

TUNNEL-KILN.

1,354,541.

Specification of Letters Patent.

Patented Oct. 5, 1920.

Application filed January 22, 1919. Serial No. 272,419.

To all whom it may concern:

Be it known that I, PHILIP DRESSLER, a subject of the Kingdom of Great Britain, residing at Zanesville, in the county of 5 Muskingum, State of Ohio, have invented certain new and useful Improvements in Tunnel-Kilns, of which the following is a specification.

My invention relates to improvements in 10 tunnel kilns of the type generally disclosed in patent of C. Dressler, No. 1,170,428 dated Feb. 1, 1916. In the type of kiln disclosed in such patent, the heating is effected by 15 means of the combustion of gas and air, which combustion takes place in chambers located on each side of the goods chamber of the kiln. In practice it has been found difficult to bring about an intimate mixture 20 of the introduced gas and the highly heated air to obtain perfect combustion.

The object of my invention, therefore, is a construction by reason of which there shall be a perfect intermixture of the introduced gas and the highly heated air at the time 25 when such gas and air is introduced into the combustion chamber.

The accompanying drawings will serve to illustrate my invention, in which:

Figure 1 is a plan section taken substantially on the line I—I of Fig. 2.

Fig. 2 is a vertical section taken on the line II—II of Fig. 1.

Fig. 3 is a transverse section taken on the line III—III of Fig. 2.

Fig. 4 is a transverse section taken on the line IV—IV of Fig. 2.

In the drawings, 5 indicates a kiln structure, which may be of any suitable construction. 6, goods chamber; 7, identical combustion chambers located on opposite sides of the goods chamber. The combustion chambers 7 are each divided into two sections, 8 in which the gas and air is mixed, and 9 in which the gas and air is burned. 45 These sections are connected together by a sleeve 10, so arranged as to permit a certain amount of longitudinal movement between sections 8 and 9.

Situated below the kiln structure is a gas 50 flue 11, which connects through vertical flues 12 located on the outside of each side of the furnace. Connected with the vertical flues and projecting into the sections 8 of the combustion chambers, are burners 13.

55 The ends of these burners have formed in

them, openings 14, by reason of which the gas introduced through the burners is projected horizontally into the sections 9 of the combustion chambers. These openings are shown as horizontally disposed slits. 60 They may be otherwise formed. Sections 8 of the combustion chambers may be built up of brick. Located in the tops of the sections 8 are valves 15 which may be operated from the outside of the kiln by means of 65 the projecting rods 16. Located in the bottom of the sections 8 of the combustion chambers, are flues 17 which communicate between the interior of the goods chamber 6 and the interior of the sections 8 of the 70 combustion chambers. The openings into the combustion chambers are provided with grates 18, the purpose of these being to diffuse the heated air passing through the flues 17 as it enters sections 8 of the combustion 75 chambers.

Sections 9 of the combustion chambers are formed with double walls 19—20, with an air space 21 between them. Flues 22, similar to flues 17, are located under these chambers, and the openings from these flues 22 into sections 9 of the combustion chambers are provided with grates 23, which correspond to grates 18. In some cases I prefer to locate in the sections 9, immediately in 85 front of the burners 13, baffle plates 24, and behind these baffle plates, openings 25, through which heated air may be introduced. 26 indicates a flue connected through a vertical flue 27 with sections 9 90 of the combustion chambers, through which the products of combustion may be conveyed away.

The operation of my improved construction will be readily understood. Gas from 95 the flue 11 is introduced through the burners 13. The gas being under pressure, acts as an injector and draws air into the sections 8 through valves 15 and flue 17, until a proper mixture of gas and air is obtained. 100 This mixture is projected through the sleeve 10 into sections 9 of the combustion chambers, where it is burned. Further air may be introduced through the flue 22 and openings 25, and the mixture of gas and air be 105 made to impinge upon the baffle plates 24 for the purpose of more perfectly effecting a mixture.

I wish it understood that I do not limit myself in any wise to the precise locations 110

of the valves or openings through which the highly heated air is introduced into the sections 8. These may be materially modified without departing in any wise from the 5 general plan disclosed.

Having thus described my invention, I claim:

1. In a tunnel kiln and in combination with the inclosing structure, combustion 10 chambers arranged on each side of the interior of the inclosing structure, said combustion chambers each divided into two sections connected by a sleeve which permits relative movement between such sections, together with means for introducing gas and 15 highly heated air into one section of each chamber and projecting it longitudinally into the adjacent section of the chamber.

2. In a tunnel kiln and in combination 20 with the inclosing structure, combustion chambers arranged on each side of the interior of the inclosing structure, each combustion chamber consisting of a mixing portion, a combustion portion and an interposed 25 sleeve, means for introducing gas and highly heated air into the mixing portion of each combustion chamber and means for projecting the mixed gas and air longitudinally through the corresponding sleeve into the 30 combustion portion of the combustion chamber.

3. In a tunnel kiln and in combination 35 with the inclosing structure, combustion chambers arranged on each side of the interior of the inclosing structure, said combustion chambers each comprising a mixing portion having a regulating valve and opening through which highly heated air may be introduced, a combustion portion having 40 openings through which highly heated air may be introduced and an exit flue for the products of combustion, and a sleeve between said mixing and combustion portions, together with means for introducing gas 45 into the mixing portion and projecting such gas and heated air from the mixing portion into the combustion portion of the combustion chamber.

4. In a tunnel kiln and in combination

with the inclosing structure, combustion 50 chambers arranged on each side of the interior of the inclosing structure, each combustion chamber divided into a mixing portion and a combustion portion, a sleeve for connecting the portions, regulatable means 55 for introducing highly heated air into the mixing portion, regulatable means for introducing gas into the mixing portion and for projecting said mixed gas and air into the combustion portion, means for checking 60 the longitudinal movement of the mixed gas and air along the combustion portion, and means for adding heated air to the mixed gas and air in the combustion portion.

5. In a tunnel kiln and in combination 65 with the inclosing structure, combustion chambers arranged on each side of the interior of the inclosing structure, each combustion chamber divided into a mixing portion and a combustion portion connected by a sleeve, means for introducing highly heated air into the top and bottom of the mixing portion, means for introducing gas into the center of the mixing portion and projecting 70 it longitudinally when mixed with air through the sleeve and into the combustion portion, and means for conveying the products of combustion from said combustion portion.

6. In a tunnel kiln and in combination 75 with the inclosing structure, combustion chambers arranged on each side of the interior of the inclosing structure, each combustion chamber divided into a mixing portion and a combustion portion connected by a sleeve, means for introducing highly heated air into the top and bottom of the mixing portion, means for introducing air 80 into the bottom of the combustion portion, means for introducing gas into the mixing portion and projecting it with highly heated air through the sleeve into the combustion portion.

In testimony whereof, I affix my signature.

PHILIP DRESSLER.
